UNITED STATES PATENT OFFICE.

CHARLES JAMES HARVEY, OF KIDDERMINSTER, ENGLAND.

WALKING MECHANISM FOR TOYS AND OTHER ARTICLES.

Application filed January 30, 1920. Serial No. 355,076.

To all whom it may concern:

Be it known that I, CHARLES JAMES HARVEY, a subject of the King of Great Britain, residing in Kidderminster, England, have 5 invented certain new and useful Improvements in Walking Mechanism for Toys and Other Articles, of which the following is a specification.

This invention relates to walking mechanism for toys and other articles and it refers to mechanism of the type forming the subject of the prior British patent granted to me under No. 108,558 and in which a frame is employed from which is supported 10 the limbs or legs, a pin or rod itself held against lateral oscillatory motion being so associated with the frame as to permit the said frame to swing and the legs to describe arcs of circles at the same time permitting 15 the frame to oscillate laterally of the pin.

The present invention has for its object certain improvements designed to simplify /and/or improve the construction of mechanism of the kind referred to.

20 In accordance with the present invention the legs form part of or are attached to an inverted substantially V-shaped element, said element as distinguished from the arrangement forming the subject of the aforesaid 25 Letters Patent, being carried directly by the toy figure or supporting body, whereby the frame and pin or the like, employed in the former arrangement are dispensed with.

The leg elements, according to the present 30 invention, are moreover so mounted or supported by the toy or supporting body as to be able to swing to advance the legs alternately with a stepping movement when the toy or supporting body is moved or drawn 35 along on a horizontal surface, the leg element at the same time being capable of both lateral and longitudinal motion to enable the rearward leg to lift for movement to advanced or forward position.

40 In order that the invention may be the better understood drawings are appended illustrating various forms of the invention in which:—

Fig. 1 is a side elevation of one form of 45 the invention as applied to a walking figure.

Fig. 2 is a front view.

Fig. 3 is a side view showing the invention applied to a representation of horse and cart.

50 Fig. 4 is a sectional view showing more

clearly the arrangement of the hind legs of the horse shown in Fig. 3.

Fig. 5 is a sectional view showing an alternative form of the invention.

Fig. 6 is a side view of one of the legs detached from the figure.

Fig. 7 is a front view of the plate whereby the legs are supported.

Fig. 8 is a front view showing a further modification.

Fig. 9 is a side view of one of the legs employed in the arrangement shown in Fig. 8.

Fig. 10 is an inverted plan view.

Fig. 11 is a sectional view on line A—A, 70 Fig. 10 and,

Fig. 12 is a diagrammatic view showing more clearly the operation of the parts.

Referring to the accompanying drawings a Figs. 1 and 2 indicates the legs of a human figure a^1 which legs comprise an inverted substantially V-shaped leg element the upper end of which a^2 is of substantial width being cut away at a^3 leaving two vertically disposed projections which, as will be 75 hereafter more fully explained, form stops whereby the extent of the lateral motion of the legs is limited.

The figure a^1 is slotted at a^4 said slot being inclined vertically from the front to the rear of the figure. In order 80 to permit the legs to be introduced into the slot the metal at the bottom of the said slot is incised at a^5 thus enabling the metal to be forced or sprung apart at this point for the passage of the part a^2 of the legs.

85 The edges of the metal after the legs have been inserted in the slot are brought together by pressure or otherwise. The width of the slot a^4 is sufficient to accommodate the part a^2 in a manner such that it is free to 90 swing both in the vertical plane and transversely of the line of the figure. In order that the figure a^1 may be supported and its oscillation prevented there is provided an extension b the lower end of which is of such 95 width that when resting upon a table or other surface it presents a bearing surface of such width as to enable the figure to be held against lateral movements.

100 In use the extension b is grasped by the hand the broad lower end on trail b' of said extension being pressed upon the surface over which the figure is moved by pushing it along, the end or trail b' serving to prevent lateral oscillatory motion of the body a .

110

It may here be stated that it is essential to the proper working of the device either in the present form or any of the other forms hereafter to be described that the following 5 conditions be observed. Referring to Fig. 12: Assuming a vertical line w to be drawn from the shoulder of the figure to the ground, it is essential that the centre line of the leg element be in advance of the vertical 10 as $w x$ when the legs are transversely or substantially transversely of the body.

As the legs assume a position longitudinally with the body the centre line of the 15 leg element changes to a position rearwardly of said vertical towards the line $w y$. In effect this permits the forward leg member to reach point z clear of the ground whilst the weight is still carried by the rearward leg member at z^1 . When the centre line 20 of the leg element changes to $w y$ the forward leg member is caused to come to the ground and the rearward leg member to be lifted at z^1 .

In the arrangement shown in Figs. 3 and 25 4 the figure is provided with four legs each pair of legs being comprised by a substantially inverted V shaped leg element such as a before referred to each pair of such legs being mounted in inclined slots formed 30 in the body c of the animal. The body c is held so that its lateral oscillation is prevented by securing it to a cart c^1 provided with wheels which are rigidly connected to a spindle c^2 . Though it is preferable it is 35 not always essential for the wheels to be fixed to the spindle. Assuming the wheels are free on the spindle, the body of the toy, if the toy progressed slowly enough, would have time to slide sideways with the 40 spindle on the wheels sufficiently to neutralize the leg action. With increase of speed however the legs work faster and therefore the tendency of the body to slide sideways is reduced to nil, or nearly so. But in all 45 cases the body must be incapable of rocking as if on a horizontal pivot.

In the arrangement just referred to the front legs of the animal assist in supporting the body c , but the back legs are so mounted 50 that whilst they may contact with the ground to secure their operation they do not assist in supporting the figure. A pair of horses or other quadrupeds may be fixed together when they will naturally support 55 each other without the necessity for providing any other means of support, a cart for example.

In the case of four legged figures the support may either be in the form of a vehicle, 60 or a second walking figure may be associated with the first figure or any other convenient form of support may be provided. In the case of four legged figures in which 65 the support in the manner above referred to is inconvenient or impossible, for example

in the case of a pig or other animal in which the provision of a vehicle would be incongruous or undesirable, the forelegs may be arranged as before described the hind legs being sufficiently spread to support the 70 figure and at the same time being so arranged as to permit of their oscillation to an extent sufficient to give an appearance of walking without upsetting the body.

The oscillating portion may carry extensions 75 representing the head, arms, or other part of the figure, which, if desired, can partake of the same movements, and said part may be made in one piece as in the examples before described, or it may be made so in two or more parts to meet the exigencies of the particular circumstances under which it is employed. The mechanism may be exposed or it may be encased or enclosed in any suitable manner.

It may be found in some instances that 85 the semi-rotation of the legs, such as takes place with the mechanism forming the subject of the aforementioned patent, is objected to, as this motion prevents the employment of legs having an outline more or less corresponding to the natural outline of the human or other leg. To overcome the objection the legs may be pivotally connected to that portion of the mechanism engaging 95 the slot of the figure.

Such an arrangement as that described is illustrated in Figs. 5, 6 and 7 where the legs indicated by d are perforated as shown at d^1 and engage a plate d^2 of the outline 100 shown in Fig. 7. The upper end of plate d^2 is cut away as shown leaving projections d^3 at each end forming steps for the purpose already explained. At the lower edge the plate is provided with recesses which 105 provide projections d^4 . The plate is disposed in an inclined perforation formed in the figure, the parts, when assembled, being substantially as shown in Fig. 5.

In the foregoing description it has been 110 assumed that the body, to which the legs are applied, is formed of thin sheet metal. In order that the mechanism may be applied to a thick body, for example the body of a wooden horse, the operating piece, or in 115 other words that portion to which in the foregoing description the legs have been attached, is made in two parts of which one may be in the form of a piece of sheet metal disposed within a slot formed transversely 120 of the body of the horse, and the other a second piece disposed beneath the body of the said horse. The slot in the body is of such width as to permit the desired rocking movement of the part at a right angle 125 to the length of the said body so as to provide the leg lifting portion of the movement only, the part disposed externally of the body partaking in the movements of the internal part and also providing the leg swing- 130

ing part of the movement, for which purpose it is preferably disposed under and clear of the said body. The legs are connected to both of the parts just above described the connection being pivotal or otherwise. The connection of the two parts of the body of the horse may be by means of a centrally disposed vertical pin or any other means permitting the necessary movements.

- 10 It may under some circumstances be necessary or advisable to avoid the cutting of a slot in the body in the manner just above stated. In order that this may be avoided an arrangement, such as that shown in Figs. 15 8 to 11, may be employed. In this case the limbs are pivotally connected at their upper ends to the body *a*, the said limbs preferably being slotted as shown at *e* Fig. 9 for the 20 certain amount of longitudinal movement on the part of the said leg. Disposed beneath the body is a cross piece *f* at each end of which there is provided an L-shaped extension the vertical limb of which freely engages a socket *f*¹ formed upon or secured to 25 the inside of the leg. One or both of the L shaped extensions are so connected to the cross piece as to permit it or them to turn in opposite directions sufficiently to follow 30 the movement of the legs.

Freely engaging the cross piece *f* is an eye *f*² pivotally secured to the body of the figure. *f*³ indicates stops designed to limit the movement of the legs.

- 35 In all cases stops are provided to prevent the leg line approaching too closely to the centre line of the body.

Alternatively the cross piece may be attached to the body by slot, pin or any other 40 connection which will permit of the required movements, and capable, if required, of supporting the weight of the body.

Whilst throughout the foregoing description the invention is described as being applied to toys, it will be understood that it 45 may be applied to other articles not intended for childrens use. For example to fancy or table articles, salt cellars for table use for instance in which the salt receptacle 50 is in the form of a cart drawn by a horse. The article may be made in silver, china or other metal or material capable of a high finish.

Having thus described my invention I 55 claim:—

1. In mechanism for walking movement, the combination of a body provided with means for preventing lateral oscillatory motion thereof; and a leg element; the leg element comprising rigid leg members, and transverse connecting means for coactively controlling the leg members for alternate movement thereof, whereby when said body is moved horizontally along on a plane surface and the leg members are contactable

with said surface one leg member is moved to body-supporting position, and the other leg member is lifted and moved forwardly with a stepping motion; the leg members being spaced apart at their upper ends in 70 adjacent opposite relation to each other and diverging downwardly.

2. In mechanism for walking movement, the combination of, a body provided with means for preventing lateral oscillatory motion thereof; and a leg element; the leg element comprising rigid leg members, and transverse connecting means for coactively controlling the leg members for alternate movement thereof, whereby when said body 75 is moved horizontally along on a plane surface and the leg members are contactable with said surface one leg member is moved to body-supporting position, and the other leg member is lifted and moved forwardly 80 and outwardly and inwardly in an arc with a stepping motion; the leg members being spaced apart at their upper ends in adjacent 85 opposite relation to each other and diverging downwardly.

3. In a mechanism for walking movement, the combination of a supporting body having means for preventing lateral oscillatory motion thereof; and a leg element, the leg element comprising a body portion 90 and rigid leg members; the leg element being carried by said supporting body and arranged to swing when the supporting body is moved horizontally upon a plane surface and the leg members are contactable with said surface and thereby to advance the leg members alternately by lateral and longitudinal oscillations thereof with a stepping movement.

4. In a mechanism for walking movement, the combination of a supporting body having means for preventing lateral oscillatory motion thereof; and a leg element, the leg element comprising a body portion and rigid leg members; the leg element being carried 105 by said supporting body and arranged to swing when the supporting body is moved horizontally upon a plane surface and the leg members are contactable with said surface and thereby to advance the leg members alternately with a stepping movement, and the leg element being arranged for lateral and longitudinal motion during said stepping movement to enable the rearward of the leg members to lift for movement to 110 forward position.

5. In a mechanism for walking movement, the combination of a supporting body having means for preventing lateral oscillatory motion thereof; and a plurality of rigid leg elements, the leg elements comprising a body portion and leg members; the leg elements being carried by said supporting body and arranged to swing when the supporting body is moved horizontally upon a 115 120 125 130

plane surface and the leg members are contactable with said surface and thereby to advance the leg members alternately by lateral and longitudinal oscillations thereof with a stepping movement.

6. In a mechanism for walking movement, the combination of a supporting body having means for preventing lateral oscillatory motion thereof; and a plurality of leg elements, the rigid leg elements comprising a body portion and leg members; the leg elements being carried by said supporting body and arranged to swing when the supporting body is moved horizontally upon a plane surface and the leg members are contactable with said surface and thereby to advance the leg members alternately with a stepping movement, and the leg elements being arranged for lateral and longitudinal motion during said stepping movement during said stepping movement to enable the rearward of the leg members to lift for movement to forward position.

7. In a mechanism for walking movement, the combination of a supporting body having means for preventing lateral oscillatory motion thereof; and a leg element; the supporting body being provided with a slot therein inclined vertically from the front to the rear of the supporting body; the leg element being substantially inverted V-shape and comprising a body portion and leg members, the body portion being received in the slot of the supporting body and arranged to provide swinging movement of the leg element when the supporting body is moved horizontally upon a plane surface and thereby to advance the leg members alternately with a stepping movement.

8. In a mechanism for walking movement, the combination of a supporting body having means for preventing lateral oscillatory motion thereof; and a leg element; the supporting body being provided with a slot therein inclined vertically from the front to the rear of the supporting body; the leg element being substantially of inverted V-shape and comprising a body portion and leg members, the body portion being received in the slot of the supporting body

and arranged to provide swinging movement of the leg element when the supporting body is moved horizontally on a plane surface and thereby to advance the leg members alternately with a stepping movement, and the leg element being arranged for lateral and longitudinal motion during said stepping movement to enable the rearward of the leg members to lift for movement to forward position.

9. In a mechanism for walking movement, the combination of a supporting body having means for preventing lateral oscillatory motion thereof; and a leg element; the leg element comprising a body portion and leg members and being carried by the supporting body and connected thereto for swinging movement, whereby when the supporting body is moved horizontally upon a plane surface the leg members are alternately advanced with a stepping movement; the center line of the leg element when the leg members are substantially transverse to the supporting body being in advance of a vertical line drawn from the point of connection of the leg element through the supporting body to said plane surface, and as the leg members during said stepping movement assume a position longitudinally with the supporting body said center line changing rearwardly of said vertical line whereby the forward leg member is permitted to reach its advanced point clear of said plane surface while the weight of the supporting body is sustained by the rearward leg member, said center line during the stepping movement changing further rearwardly of said vertical line whereby the forward leg member is caused to come to rest upon the plane surface and the rearward leg member to be lifted therefrom for movement to advanced position.

In witness whereof I have hereunto set my hand in the presence of two witnesses.

CHARLES JAMES HARVEY.
